UNITED STATES PATENT OFFICE.

DAVID MCNAIR, OF BOSTON, MASSACHUSETTS, ASSIGNOR TO THE ROXBURY CARPET COMPANY, OF SAME PLACE.

DESIGN FOR CARPETS.

SPECIFICATION forming part of Design No. 11,611, dated January 20, 1880.

Application filed December 23, 1879. Term of patent 3½ years.

To all whom it may concern:

Be it known that I, DAVID MCNAIR, of Boston, in the county of Suffolk and State of Massachusetts, have invented a new and original Design for Carpets, of which the following is a specification.

The nature of my design is fully shown in the accompanying photographic illustration. It consists of the floral designs and leaves or foliage, forming a pattern too intricate for specific description.

I claim—

The design for carpets, as shown.

In testimony whereof I have signed my name to this specification, in the presence of 15 two subscribing witnesses, this 16th day of December, 1879.

DAVID MCNAIR.
